[57] CLAIM

The ornamental design for combined ice skate and brackets, as shown and described.

DESCRIPTION

FIG. 1 is a left side elevational view of a combined ice skate and brackets embodying our new design, the broken line showing of the boot is for illustrative purposes only and forms no part of the claimed design;

FIG. 2 is a top plan view thereof;

FIG. 3 is a right side elevational view thereof;

FIG. 4 is a bottom plan view looking upwardly at the ice skate blade support and brackets of FIG. 1;

FIG. 5 is a front end view thereof; and,

FIG. 6 is a rear end view thereof.

FIG. 2

FIG. 3

FIG. 4

FIG. 5

FIG. 6
